UNITED STATES PATENT OFFICE.

HARRY P. STONE, OF NEW YORK, N. Y., ASSIGNOR OF ONE-HALF TO CHARLES O. STERLING, OF WASHINGTON, DISTRICT OF COLUMBIA.

DESIGN FOR A BADGE.

SPECIFICATION forming part of Design No. 29,863, dated December 27, 1898.

Application filed February 2, 1898. Serial No. 668,893. Term of patent 3½ years.

To all whom it may concern:

Be it known that I, HARRY P. STONE, a citizen of the United States, residing at New York, in the county of New York and State 5 of New York, have invented and produced a new and original Design for a Badge; and I do hereby declare the following to be a full, clear, and exact description of the same, reference being had to the accompanying drawing, forming a part thereof.

The design is adapted especially for badges of that sort intended to distinguish one class of society or persons from another—as, for instance, the students or adherents of one 15 college from those of another.

The figure in the drawing shows a front elevation of a badge illustrating my design.

As shown by the drawing, the leading or essential feature of my design comprises two 20 substantially-circular disks A B of practically like size, but of contrasting facial colors and located adjacent each other. On the face of each disk is represented a symbol C, the colors of which symbols also contrast, the sym-

bol on disk A being of the same color as the 25 face of disk B, while the symbol on disk B is the same color as the face of disk A. Wide bands or ribbons D extend upward—one from each of the disks A and B—and converge toward their upper ends, where they are united 30 in the form of a rosette or ornament d.

The symbols C illustrated are in the form of a fanciful letter Y. The ribbon which extends from disk A is the same color as disk B and the ribbon which extends from disk B 35 is the same color as the disk A.

Having thus described my invention, what I claim, and desire to secure by Letters Patent, is—

The design for a badge, substantially as 40 shown and described.

In testimony whereof I affix my signature in presence of two witnesses.

HARRY P. STONE.

Witnesses:

W. MARTIN CHEESMAN,
